BALANCED THERMOSTAT

Hazor J. Smith, Springfield, Mass., assignor to
Superstat Company, Springfield, Mass., a corporation of Massachusetts

Application February 23, 1933, Serial No. 658,051

12 Claims. (Cl. 200—140)

This invention relates to condition-responsive devices and more particularly to a pressure-responsive device of the expansible bellows type.

An object of the invention is to provide a pressure-responsive device having high sensitivity.

Another object is to provide a device of the above-mentioned type which may be readily adapted for a variety of pressure ranges.

Another object is to provide a cheap, simple, efficient and dependable device of the type above indicated.

Although the novel features which are believed to be characteristic of this invention will be more particularly pointed out in the claims appended hereto, the invention itself, as to its objects and advantages and the manner in which it may be carried out, may be better understood by referring to the following description taken in connection with the accompanying drawing forming a part thereof, in the various figures of which like reference characters have been used to designate like parts.

In the drawing:

Figure 1 is a side elevation, partly in section, of a thermostat illustrating one embodiment of the invention;

Figure 2 is a section taken on the line 2—2 of Figure 1; and

Figure 3 is a detail of the switch arm and operating contacts.

Referring to the drawing, the invention is shown as embodied in a pressure-responsive device comprising a housing 10, which is mounted on a bracket 11 by suitable means, such as a clamp 12, which is adapted to surround said housing and to be secured to said bracket in any desired manner (not shown). The housing 10 is sealed by a cap 13, which may be seated in a flange 14 formed on said housing.

An expansible bellows 15 having a comparatively stiff cover 16, hermetically sealed thereto to form a variable pressure chamber, is mounted within the housing 10. A plunger 17 is rigidly secured to the cover 16 and extends through a bushing 18 carried by the cap 13. A second metallic bellows 19 is seated in a recess 20 in the cover 16 and is secured between the cap 13 and the plunger 17 to form a glandless seal for the plunger. The bellows 19 also serves in conjunction with the cap 13 and the bellows 15 to form a hermetically sealed balancing chamber 21 within the housing 10 and external to the bellows 15.

To operate as a thermostat, for example, the bellows 15 may be charged with a substance hav-

ing a substantial change in vapor pressure within the temperature range involved in the operation of the device. The amount of charge is preferably such that the vapor remains saturated, in the presence of its liquid, only throughout the operating range, inasmuch as the differential change in vapor pressure of the saturated vapor with respect to temperature is greater than the differential change in gas pressure of the unsaturated vapor.

Various substances may be employed for this purpose, depending upon the operating range of the instrument. Methyl chloride has been found suitable for an outdoor thermostat having a temperature range of, for example, from —10° F. to +65° F. Various other substances which may be employed, together with representative temperature ranges, are as follows:

Isobutane	10° F.—85° F.	20
Butane	33° F.—100° F.	
Ethyl chloride	60° F.—140° F.	
Sulphuric ether	105° F.—180° F.	
Carbon tetrachloride	140° F.—220° F.	
Alcohol	180° F.—260° F.	25

All of the above representative substances have a substantial vapor pressure within the range of temperatures specified and possess a comparatively high differential pressure with respect to temperature, provided the amount of the charge is such that the vapor always remains saturated. It is obvious that other substances having similar properties may be employed.

The chamber 21 may contain any counter-balancing gas, such as air. The relationship between the size, gas pressure and change of volume of the balancing chamber 21 is preferably such that the pressure-volume curve of the gas within the chamber follows the pressure-temperature curve of the substance within the bellows 15.

Adjustment for this purpose may be made by introducing into the chamber 21 a liquid, such as alcohol, so as to reduce the gas volume of the chamber without reducing the total volume change of the chamber. By this means the ratio of the maximum to minimum gas volumes in the operating range of the device may be raised to any desired value. The liquid reduces the movement of the bellows per degree of temperature change and consequently increases the temperature range of the device. It also permits the use of a bellows that is comparatively long with respect to the total change in length during operation.

For example, if the liquid occupies 0.9 of the

volume of the bellows in its expanded position, it is evident that a movement of only 0.1 of the total length of the bellows changes the gas volume from a maximum to 0 and changes the gas pressure from a minimum to infinity.

As a further illustration, the change in vapor pressure of methyl chloride between 0° F. and 65° F. is equal to approximately 58 pounds per square inch. Hence, if the bellows 15 is charged 10 with methyl chloride, the volume ratio of the balancing chamber 21 should be such that a pressure differential of 58 pounds is obtained in the same range.

The adjustment is preferably made at the lowest working temperature so as to avoid the necessity for allowing for shrinkage of the gas upon reduction in temperature. For convenience, the adjustment may be such that the counterbalancing gas is at atmospheric pressure at the lowest working temperature. The liquid may be introduced from any suitable source (not shown) through an inlet pipe 25, provided with a valve 26. When a sufficient amount has been introduced to produce the desired operating characteristics, the pipe 25 may be removed and the opening in the cap 13 may be sealed by suitable means, such as by solder.

The arrangement is such that the vapor pressure within the bellows 15 is nearly equal to the gas pressure within the chamber 21. It is possible, therefore, to utilize a bellows having extreme sensitivity because of the relatively small pressure differential to which it is subjected. The bellows 15 may accordingly be formed with a comparatively thin wall and may be made much more flexible and sensitive than would be the case if it were exposed externally to the atmosphere. The bellows 19 is of small diameter and of comparatively great length and may accordingly be made to withstand the difference between the pressure in the chamber 21 and the pressure of the outside atmosphere without being unduly rigid.

With a rise in temperature, the pressure of the substance within the bellows 15 increases and the bellows expands to equalize this pressure against the pressure in the chamber 21, thereby producing longitudinal motion of the plunger 17. Upon a fall in temperature, the reverse action takes place.

The plunger 17 may be connected to any suitable mechanism in which mechanical movement is desired in response to temperature or pressure changes, such, for example, as a heat control (not shown). It is illustrated, for example, as applied to the control of a reversing and progressive switch mechanism comprising a lever 30 which is connected to the plunger 17 by suitable means, as by a pin 31 engaging a slot 32 in said lever. The lever 30 is pivoted about an eccentric stud 33 on a pin 34, which is supported on a base plate 35 in any convenient manner, as by screws 45, engaging flanges 46 formed on or secured to the pin 34. The base plate 35 carries a plurality of sets of contacts 36 and 37 and may be secured to the bracket 11 by suitable means, such as screws 38.

The lever 30 carries a pair of contact members 40 and 41, which are adapted to cooperate with contact members 42 and 43 respectively, carried by a switch arm 44, which is pivoted about the pin 34. The switch arm 44 carries brushes 51 and 52, which are electrically connected to the contacts 42 and 43 respectively and are adapted 75 to selectively engage the sets of contacts 36 and

37 respectively. The contacts 40 and 41 may be connected by flexible connectors 55 and 56 to binding posts 57 and 58 respectively. The binding posts together with the sets of contacts 36 and 37 may be connected to a multiple socket 60, which facilitates connection of the device to an operating unit (not shown).

The eccentric mounting of the lever 30 causes the contacts 40 and 41 to slide over the contacts 42 and 43, respectively, when the switch arm 44 10 and the lever 30 are oscillated, thereby tending to maintain the contacts in clean condition.

The above-described switch mechanism is adapted to constitute a reversing and progressive switch, which is operated by the thermostat and 15 may be used to control a reversible condition-control device of any desired type, for example, a reversible motor control unit disclosed in my copending application Serial No. 657,237, filed February 17, 1933.

The above-described device has been found to be particularly sensitive and powerful and may be adjusted to produce any desired movement of the plunger 17 for a given change in temperature. It is accordingly particularly adapted 25 to heat-control systems and the like, wherein a fine control of temperature is required. It is also adapted for various other uses, which will be apparent to a person skilled in the art.

The invention has been specifically described 30 for convenience as embodied in a thermostat, but it is obvious that it is applicable to any variable pressure device. The bellows 15 may, for example, be charged with steam from a steam line and may operate in response to pressure variations thereof.

Although a certain embodiment of the invention has been disclosed for purposes of illustration, it is to be understood that the various parts thereof may be varied without departing from 40 the spirit of the invention, and that the invention is only to be limited in accordance with the following claims when interpreted in view of the prior art.

I claim:

1. A thermostat comprising an expansible bellows, a housing surrounding said bellows and forming a hermetically sealed balancing chamber, a plunger operatively associated with said bellows and extending through said housing for longitudinal movement with respect thereto and being hermetically sealed to said housing.

2. A thermostat comprising an expansible bellows, a housing surrounding said bellows and forming a balancing chamber external thereto, 55 a plunger operatively associated with said bellows and extending through said housing, and a second expansible bellows associated with said plunger and forming a glandless seal with said housing.

3. A thermostat comprising an expansible bellows, a housing surrounding said bellows and forming a balancing chamber external thereto, a plunger operatively associated with said bellows and extending through said housing, and a second expansible bellows associated with said plunger and forming a glandless seal with said housing, said first bellows being adapted to withstand a small pressure differential and said second bellows being adapted to withstand a greater 65 pressure differential.

4. A thermostat comprising an expansible bellows having a cover hermetically sealed thereto, said cover having a recess formed therein, a housing surrounding said bellows and forming a 70

hermetically sealed balancing chamber external to said bellows, a plunger secured to said cover and seated in said recess and extending through said housing, and a second bellows interconnecting said plunger with said housing and hermetically sealing the same, said second bellows being of less diameter than said first bellows and being of comparatively great length and adapted to withstand a greater pressure differential than

10 said first bellows.

5. In combination, a temperature-responsive device comprising an expansible bellows, a housing forming a balancing chamber external to said bellows, a plunger operatively associated 15 with said bellows and extending through said housing, a switch means comprising a stationary plate carrying a set of progressive contacts, a brush pivoted to progressively engage said contacts, and means associated with said plunger for 20 controlling the position of said brush.

6. A switch mechanism comprising a contact, a pivoted lever carrying said contact, a second contact, a switch arm pivoted eccentrically of 25 said lever and carrying said second contact, and means for causing pivotal movement of one of said contacts, said eccentric mounting being adapted to cause relative sliding movement between said contacts for maintaining said contacts in clean condition.

30 7. A switch mechanism comprising a pivoted switch arm carrying a pair of contacts and a lever pivoted eccentrically of said arm and carrying a second pair of contacts adapted to cooperate with said first pair of contacts to form a 35 reversing switch, the eccentric mounting causing relative sliding movement between said first and second pairs of contacts when said arm and lever are oscillated, whereby said contacts are maintained in clean condition.

40 8. A pressure-responsive device comprising an expansible bellows, a rigid housing surrounding said bellows to form a balancing chamber, the pressure in which is varied by movement of said bellows, said chamber being partly filled with a 45 liquid adapted to decrease the gas volume there-

of and to increase the volume ratio of the chamber within the operating range thereof while permitting the use of a long, flexible bellows.

9. A pressure-responsive device comprising expansible means forming a variable pressure chamber, said chamber being partly filled with a liquid adapted to displace a part of the gas content and to reduce the total gas volume of the chamber while permitting the use of a long, flexible bellows, whereby the differential gas pressure with respect to the total volume of said chamber is increased.

10. A variable pressure device comprising a bellows containing a variable pressure medium, a housing surrounding said bellows and sealed to 15 form a balancing chamber, said chamber containing a liquid and a gas, said liquid being adapted to decrease the gas content of said chamber, whereby the volume ratio of the gas within the operating range is increased with respect to 20 the total volume ratio of said chamber, said liquid being in such quantity as to cause the volume-curve of the gas to correspond to the pressure-curve of said variable pressure medium within a selected operating range.

25 11. A housing having expansible means adapted to form a variable volume chamber, said chamber containing a gas and a liquid, said liquid being adapted to displace a part of the gas and to reduce the gas volume by a constant 30 amount throughout the operating range of the device, whereby the pressure-change of the gas with respect to the total volume-change of said chamber is increased.

35 12. A housing having expansible means adapted to form a variable volume chamber, said chamber containing air and alcohol, said alcohol being adapted to displace a part of the air and to reduce the air volume by a constant amount 40 throughout the operating range of the device, whereby the pressure-change of the air with respect to the total volume-change of said chamber is increased.
